Primary Examiner — Randall H Gholson*(74) Attorney, Agent, or Firm* — Morgan, Lewis & Bockius LLP**CLAIM**

The ornamental design for a helmet retention system, as shown and described.

DESCRIPTION

FIG. 1 is a front perspective view of a helmet retention system in accordance with our new design;

FIG. 2 is a top plan view thereof;

FIG. 3 is a bottom plan view thereof;

FIG. 4 is a left-side elevational view thereof; and,

FIG. 5 is a right-side elevational view thereof.

The broken lines immediately adjacent the shaded areas represent the bounds of the claimed design while all other broken lines are directed to environment and are for illustrative purposes only; the broken lines form no part of the claimed design.
